UNITED STATES PATENT OFFICE

2,425,397

BELT FOR GARTERS AND SANITARY PADS

Leo Roseman, Newark, N. J.

Application August 18, 1943, Serial No. 499,062

5 Claims. (Cl. 128—291)

1

This invention relates in particular to a hose supporting belt and a support for surgical bandages or sanitary pads, constructed so as to permit natural body movements without undue or uneven strains on the belt or support, the hose or the bandage and without shifting of the latter.

A hose or stocking supporter in general similar to that mentioned above, is described and claimed in my United States Patent No. 2,377,651, dated June 5, 1945. That hose supporter comprises a flexible, non-elastic connector such as a tape that has its ends connected to the front and rear portions of the stocking and has its intermediate portion slidable in a guide on a belt, so that, for example, as the rear end of the tape is pulled downwardly by sitting or bending the body of the wearer, the front end will be pulled upwardly, whereby the downward pull at the rear is compensated by relaxation of the tension at the front and the strains at the front and rear engaged portions of the stockings are equalized.

Prime objects of my invention are to provide a novel and improved support for a surgical bandage, for example a sanitary pad, which shall comprise a waist-encircling belt and a suspension strap that shall have its ends adapted for connection to the front and rear ends of the bandage or pad and its intermediate portions slidable in a guide on said belt so that said strap may slide girthwise of the body to accommodate body movements of the wearer and to prevent shifting of the bandage or pad; and to provide a novel and improved combination of a stocking supporter and a surgical bandage supporter of the character hereinbefore described such that one and the same belt can serve for both the stocking supporter and the support for the surgical bandage and the combination shall be simple, inexpensive and reliable.

In structures of this character, the tapes must repeatedly slide back and forth in the guides on the belt and the end portions of the tapes bend or turn at approximately right angles to the intermediate portions and to the belt at the zones where the tapes enter and leave the guides on the belt, as a consequence of which excessive strain on and frictional wear of the tapes and the guides at said zones may occur unless some means is provided to alleviate said strain and the frictional contact of the tapes with the guides. Moreover, the excessive friction impedes or hinders sliding of the tapes in such a way that the support does not properly accommodate movement of the body.

Therefore further objects of my invention are to provide a novel and improved guide element

2

for said tapes, to reduce the strains upon said tapes and the friction incident to contact of the tapes with the guides; to provide a curved tubular, flexible guide element attached to the belt and through which the tape may be threaded, such that there shall be a minimum of frictional resistance to sliding of said tape and the guide may accommodate itself to different angular relations between the end portions of the tape and the belt

10 to reduce the strains imposed on the tape and to ensure a minimum of impedance to sliding of said tape relatively to the belt, and to utilize for such a guide member a bias woven fabric tube having its end portion turned inwardly to provide a double thickness in walls of the tube and to prevent fraying of the fabric at the end of the tube.

Other objects are to provide novel and improved means to facilitate attachment of said tape and guide members to and removal thereof from the belt and adjustment of the guide elements girthwise on the belt, so that the bandage support can be laid aside when not needed and the guide members can be adjusted to properly locate the ends of the tapes girthwise of the body for attachment to the stockings or sanitary pad, and also to permit easy laundering of the belt and tapes; and to obtain other advantages and results that will be brought out by the following description in conjunction with the accompanying drawings in which

Figure 1 is a perspective view of a sanitary belt embodying my invention.

Figure 2 is an enlarged transverse vertical sectional view on the line 2—2 of Figure 1.

35 Figure 3 is a further enlarged fragmentary perspective view of a portion of the belt and one of the guide members showing the guide member in longitudinal section.

Figure 4 is a fragmentary transverse vertical sectional view on the line 4—4 of Figure 3.

Figure 5 is a view similar to Figure 1 showing a modification of the invention.

Figure 6 is a perspective view of another modification of the invention.

45 Figure 7 is a fragmentary sectional perspective view of a modification of the guide members.

Figure 8 is an enlarged transverse vertical sectional view on the line 8—8 of Figure 7.

Figure 9 is a view similar to Figure 7 showing a further modification of the invention.

50 Figure 10 is a side elevational view of a modified combination of the equalizing tape and a guide member.

Figure 11 is a view similar to Figure 10, illustrating portions in side elevation and showing a

modification of the structure depicted in Figure 10, and

Figure 12 is a horizontal sectional view on the line 12—12 of Figure 11.

Specifically describing the embodiment of the invention illustrated in Figures 1 to 3 inclusive the reference character A designates a support to encircle the body above the hips, in which is mounted a suspending strap or equalizing tape B to be connected at its extremities to opposite ends of a surgical bandage, for example, a sanitary pad C, so that the equalizing tape and the support may freely move relatively to each other to compensate for various positions of the body such as those occurring during walking, sitting and bending.

The support A preferably constitutes a waist-encircling belt and comprises a length of textile fabric I which has its longitudinal edge portions turned inwardly at 2. The belt has guide means for the equalizing tape B which is shown as comprising a plurality of guide elements in the form of cross strips 3 of fabric which are secured to the main strip I in spaced relation circumferentially or lengthwise of the strip in a row. The cross strips 3 are secured at spaced points in their lengths to the main strip I as by lines of stitches 4 and the portions of the cross strips between the stitches 4 are free and spaced from the main strip as clearly shown in Figure 2. The cross strips thus serve as guide elements for the equalizing tape B.

The equalizing tape B may be of any suitable construction but preferably comprises a length of suitable woven fabric tape or a tubular woven fabric lace, which is threaded between certain of the cross strips 3 and the main strip I with each end of the tape projecting from the belt. Preferably the ends of the cross strips 3 are located between the main portion and the inturned edge portions of the strip I so that said inturned end portions provide a channel between them in which the tape B is nested and slidable, said channel and the cross strips 3 thus forming a guideway. With this construction the belt is smooth and devoid of projections or protuberances. If desired a reenforcing or backing strip 5, which may be of cushioning material, may be secured to the strip I.

The end portions of the tape are so related to the belt that when the belt is applied to the body, one of said end portions will be located at the front of the body while the other end portion will be located at the rear of the body, the intermediate portion of the tape B between said end portions being slidable along half of the circumference of the belt. It is necessary that the end portions of the tape be bent or turned downwardly out of the plane of the belt for connection to the sanitary pad C or the like, and it is desirable that some means be provided to reduce the strains on and frictional wear of the tapes at certain zones of bending or turning where the tapes enter or leave the guide means.

For this purpose I provide a tubular flexible guide member 6 at each end of the guideway through which the corresponding end portion of the tape B is threaded. Preferably each guide member 6 comprises a length of bias woven seamless, collapsible and expansible fabric tube one end of which is attached to the belt and is directed circumferentially thereof in line with the guide channel, while the other portions are curved downwardly out of the plane of the belt.

It is desirable that the guide member be at-

tached to the belt at the upper side of the guide member, as by squeezing or flattening portions of the walls of the tube as indicated at 6 in Figure 4 and passing stitches 7 through said walls and the belt. Preferably a line of superposed or tying stitches is utilized to ensure a secure attachment of the guide to the belt. This leaves the lower side of the tubular guide member yieldable and flexible as shown in Figures 3 and 4 so as to reduce to the minimum the friction incident to the contact of the tape with the guide member and to ensure a minimum of impedance to sliding of the tape through the guide member at the bend of the tape. It is also desirable that the end portions of the fabric tube be turned inwardly as indicated at 8 in Figure 3, this providing a double thickness in the walls of the tube and also preventing fraying or unraveling of the fabric at the end of the tube.

As shown, suitable devices D are provided for attaching the ends of the equalizing tape B to the sanitary pad C. These devices may be fabric tabs to be pinned to the pad as shown in Figure 1, or may constitute metal or plastic grippers as shown in Figure 5. If desired, the end of the tape B may be directly connected to the device D, or suitable adjusting clamps or clasps E, for example such as described in my copending application Serial No. 455,446, filed August 20, 1942, may be utilized to permit the length of the tape between the belt and the end of the pad to be adjusted as desired. Generally such an adjustment at only one end of the equalizing tape is necessary, although both ends may be made adjustable if desired.

Any suitable means may be provided for attaching the belt to and removing it from the body and for adjusting the belt to fit the body; for example the ends of the belt may be separably overlapped as indicated at F and separably connected by head and socket fasteners or hooks and eyes, or a buckle may be used for separably connecting the ends of the belt.

When the belt is applied to the body, the device D at the front of the tape B is connected to the front end of the pad C, while the device D at the rear end of the tape is attached to the rear end of the pad. The length of the tape initially will be adjusted, as by the clamp E, to snugly hold the pad in proper position when the body is erect.

As the body moves from one position to another the equalizing tape B will slide relatively to the belt A through the guideway provided by the strip I, the cross strips 3 and the guide members 6 so as to equalize the strains and pulls on the ends of the pad and to permit movements of the body without shifting of the pad. The guide members 6 and tape B as described have been found to be long-lived, permitting repeated reciprocation of the tape under tension through the guide member many thousands of times without appreciable evidence of wear, and the life of the equalizer tape is many hundreds of times greater when sliding in said guide members than when sliding directly in contact with a cross strip 3. Furthermore, the tape freely slides through the curved guide member so that there is a minimum of tendency to binding of the tape at the point where the tape enters and leaves the guideway.

A modification of the invention is shown in Figure 5 where two equalizing tapes G for garters are provided in the same guideway of the belt A in which the equalizing tape B is arranged. These tapes G may be of the same construction

and arranged in the guideway in the same manner as the tape B, there being one tape for each stocking and each tape having at its opposite ends, suitable devices such as clasps 10 for connecting the tape to the front and rear portions of the corresponding stocking. A separate guide member 11 is attached to the belt A for each end of each tape G, said guide members being of the same construction and secured in the same manner to the belt as the guide members 6. However, the guide members 11 are longer than the guide members 6 so that they contact with the body and prevent frictional rubbing of the skin by the end portions of the tapes G. This structure and function in general is described and claimed in my copending application Serial No. 486,145, filed May 8, 1943.

The tape B and one of the tapes G are located in frictional contact with each other in the same guideway as shown at the right hand side of Figure 5, although the ends of the two tapes have different guide members 6 and 11.

With this construction the movement of the garter equalizing tape G has a tendency to facilitate sliding of the tape B. It will be noted that the forces applied to the tape G are greater than those applied to the tape B upon body movements so any tendency of the tape B to stick or remain stationary during a body movement will be overcome by the frictional contact with the tape B of the garter tape G.

Furthermore, it will be observed that the construction provides a compact, simple, and reliable combination in one and the same belt of an equalizing garter and an equalizing support for a sanitary pad.

If desired the garter equalizing tapes and the sanitary pad equalizing tape may be mounted in separate guideways in the same belt, as shown in Figure 6. Here the belt H has guideways I for the two garter equalizing tapes K, and another guideway L for the sanitary pad equalizing tape M. Conveniently the two guideways may be formed by attaching to the strip 12 which corresponds to the strip 1, cross strips 13, corresponding to the strips 3 but longer, and then securing to the strip 12, in transverse relation to the cross strips 13, a circumferential or longitudinal strip 14.

In this way, the guideway L is formed between the strip 14 and one of the inturned edges 15 of the main strip 12 while the other guideways I are formed between the strip 14 and the other inturned edge 15 of the main strip.

Figure 6 also shows that the guide member 6 for the equalizing tape of the sanitary pad may be omitted if desired. As shown one of the cross strips 13 serves as a guide member at the bend where the equalizing tape enters or leaves the guideway.

In the constructions so far described, it will be observed that in attaching and removing the equalizing tapes to and from the belt, they must be threaded through the guideways beneath the cross strips 3 and through the guide members 6 and 11. If desired, however, the cross strips 3 or the like may be omitted or separably attached to the main strip 1 of the belt and the guide members such as 6 and 11 may be separably attached to the belt to permit removal of the tapes by simple detachment of the guide members. Many different constructions may be utilized for making this separable attachment. As shown in Figures 7 and 8 the guide member N is permanently secured to a strip 16 which also

carries separable fastener elements 17 such as the hooks of hook and eye fasteners. The complementary separable fastener elements comprise pockets 18 in a strip 19 of fabric which is secured to the belt O. With this construction it will be observed that the equalizing tape P may be permanently threaded through the guide members N and can be easily attached to and removed from the belt with the guide members by simply inserting and removing the hooks 17 into and from the pockets 18 respectively. This is especially advantageous where it may be desirable to remove the sanitary pad equalizing tape but continue to wear the belt as a garter belt. Moreover, the use of the pocket strip avoids the presence of metal and objectionable protuberances. Also the structure facilitates laundering of the parts.

If desired, by providing extra separable fastener elements on the belt, the position of the guide members may be adjusted circumferentially of the belt to accommodate variations in body girth and permit accurate location of the pad or garter clasps girthwise of the body, especially to compensate for adjustments in the length of the belt.

With this construction, it will be observed that the guide member N will be held in spaced relation to the belt and above the plane of the guide member Q for the garter equalizer tape, so that the tape P for the sanitary pad will be held out of frictional contact with said guide member Q.

It will be understood that the equalizing tapes for the garters may be separably attached to the belt in the same manner.

If desired the equalizing tapes may be entirely enclosed within the belt as shown in Figure 9 where the belt is shown as formed of two pieces of fabric 20 and 21 stitched together to form a guide channel 22 between them in which the equalizing tape R may be slidably mounted. The guide member S may have one end secured between said pieces of fabric and the other end may project through a gap 23 between the lower edges of said pieces.

Other modifications in the details of construction of the invention will occur to those skilled in the art as within the spirit and scope of the invention.

In known sanitary belts that have included elastic for holding the pad against movement, the force applied to the elastic to accommodate body movements and at the same time prevent slipping of the pad, is two or three times greater than that applied to the equalizer tape of my invention. This advantage of my invention over the prior devices is due in large part to the guide members 6, 11, N, etc. My guide members also are advantageous in the same way over more current sanitary belts which have pad-suspending tapes slidable in belts or other supports.

As shown in Figures 5 and 10, for the purpose of adjusting the length of the garter equalizing tape between the stocking-attaching devices 10, the guide members 11 may extend from the belt to the extremities of the respective tapes G and be fastened to the tapes as by stitches 25; and both the tape and the associated guide member may be threaded through the adjusting device T, like the device E, so that the length of both the tape and the guide can be adjusted at the same time and the same amount. While such a construction generally is necessary and preferable only at the rear end of the tape, either the rear end or the front end, or both ends, of the

tape may be made adjustable as described. If desired the ends of the equalizing tape and guide members for the sanitary pad may be constructed in the same way.

If desired, as shown in Figures 11 and 12, the free end of the guide member 26 may be turned inwardly as indicated at 27 and the thickened end portion of the combined guide member and equalizer tape thus produced will abut the cross piece 28 of the adjusting device T and prevent accidental disconnection of the combined guide and equalizer tape from the adjusting device.

Also, said free end portion of the combined guide member and tape may be held in slidable side-by-side relation to the main portion of the guide member by suitable means, for example, a loop 29 which is attached to said free end portion and slidably embraces said main portion. The loop may be formed of thread, fabric, plastic or any suitable material. With this construction, as the guide member and tape are pulled through the adjusting device T, the loop 29 will slide along the guide member and hold said free end portion neatly in an out-of-the-way position.

To avoid circumlocution in the claims the term "article of apparel" is used to include the sanitary pad, stocking, or other articles that might be supported by the belt as described.

What I claim is:

1. In combination a support to encircle the body, and a tape having devices at its end portions to be connected to an article of apparel, said support having guide means in which the intermediate portion of said tape between said end portions is slidable, said guide means including tubular flexible guide members arranged spaced circumferentially of the support, one for each end portion of said tape with one end of each guide member directed circumferentially of said support and the other portions of said guide member curved downwardly away from the support, the walls of each guide member at the upper side and over a portion of the circumference thereof being squeezed together, a line of superposed tying stitches penetrating said squeezed-together portion and said support for securing the upper side of said end of each guide member to said support, the lower side of each guide member being yieldable and flexible, and said tape being threaded through both of said guide members with its end portions projecting from the other ends of the respective said guide members.

2. The combination of a support to encircle the body, a tape having devices at its end portions to be connected to an article of apparel, said support having guide means in which the intermediate portion of said tape between said end portions is slidable, said guide means including tubular flexible guide members arranged at the front and rear of said support respectively, one for each end portion of said tape with one end of each

guide member directed circumferentially of said support and the other portions of said guide member curved downwardly away from the support, a line of stitches extending lengthwise of each guide member along the upper side of said end to secure said guide member to said support and so that the lower side of said guide member is yieldable and flexible, said tape being threaded through both of said guide members with its end portions projecting from the other ends of the respective said guide members.

3. The combination of a support to encircle the body, a tape having devices at its end portions to be connected to an article of apparel, said support having guide means in which the intermediate portion of said tape between said end portions is slidable, said guide means including flexible soft guide tubes arranged in spaced relation circumferentially of said support, one for each end portion of said tape with one end of each guide tube directed circumferentially of said support and the other portions of said guide tube curved downwardly away from the support, and fastening means extending along and passing through the upper side of said end of each guide tube and into said support to secure said tube on said support and so that the lower side of said tube is yieldable and flexible, said tape being threaded through both of said guide tubes with its end portion projecting from the other ends of the respective said guide tubes.

4. The combination set forth in claim 3 wherein each said guide tube comprises a bias woven fabric tube the walls at the upper side and over a portion of the circumference of which are squeezed together, and said means for securing the tube to said support comprises a line of stitches passing through said squeezed-together portion of the walls of the tube into said support.

5. The combination set forth in claim 3 wherein each said guide tube has one end portion turned inwardly of the tube to form a double thickness in the walls of the tube and to prevent fraying of the end of the tube and said means for fastening each guide tube to said support passes through said double thickness in the walls of said tube.
